UNITED STATES PATENT OFFICE.

WILBER H. THARP AND ALBERT T. ELLIAS, OF LEWISTON, IDAHO.

TOILET ARTICLE.

1,244,798.

Specification of Letters Patent. Patented Oct. 30, 1917.

Application filed January 22, 1917. Serial No. 143,699.

To all whom it may concern:

Be it known that we, WILBER H. THARP and ALBERT T. ELLIAS, citizens of the United States, residing at Lewiston, in the county 5 of Nez Perce and State of Idaho, have invented certain new and useful Improvements in Toilet Articles, of which the following is a specification, reference being had to the accompanying drawings.

10 This invention relates to certain improvements in toilet articles and has relation more particularly to a device of this general character especially designed and adapted for use for shaving purposes; and it is an object 15 of the invention to provide a novel and improved article of this general character comprising a case having adjustable means therein adapted to support a brush and a cake of soap, and wherein said brush and 20 soap may be entirely confined within the case or either of the same extended outwardly of the case when required for use.

It is also an object of the invention to 25 provide an article of this general character having novel and improved means whereby a brush and a cake of soap are conveniently and effectively protected, when not in use, against foreign substances which would otherwise render the same unsanitary.

30 The invention consists in the details of construction and in the combination and arrangement of the several parts of our improved toilet article whereby certain important advantages are attained and the device 35 is rendered simpler, less expensive and otherwise more convenient and advantageous for use, all as will be hereinafter more fully set forth.

The novel features of the invention will 40 hereinafter be definitely claimed.

In order that our invention may be the better understood, we will now proceed to describe the same with reference to the accompanying drawings, wherein—

45 Figure 1 is an elevational view of a toilet article constructed in accordance with an embodiment of our invention and in closed adjustment;

Fig. 2 is a longitudinal sectional view taken through the device as illustrated in 50 Fig. 1 with the parts in elevation;

Fig. 3 is a fragmentary view partly in elevation and partly in section illustrating the cake of soap in extended position;

Fig. 4 is an end elevational view of the 55 device as illustrated in Fig. 3 with the cake of soap removed; and

Fig. 5 is a fragmentary transverse sectional view illustrating the mounting of one of the operating members as herein included. 60

As disclosed in the accompanying drawings, 1 denotes a tubular case, preferably cylindrical in form and having its opposite ends open. The opposite end portions of the case 1 are adapted to be closed by the 65 caps 2 herein set forth as of a slip type.

At diametrically opposed points the case 1 is provided with the longitudinally disposed elongated slots 3 through which extend the operating members 4 carried by the 70 sleeve or barrel 5 slidably mounted within the case 1. The operating members 4 may be as desired but it is preferred that the same comprise lengths of flat bendable material having one end portion suitably anchored to the sleeve or barrel 5 and which, after being directed through the slots 3, are returned upon themselves, as at 6, to afford heads or the like to facilitate the desired relative movement between said sleeve 80 or barrel 5 and the case 1. In applying the sleeve or barrel 5 the length of material from which the members 4 are produced are caused to snugly conform to the periphery of the sleeve or barrel 5 with their outer or 85 free ends arranged to one side of the slots 3. It will be perceived that upon imparting 90 relative rotation to the case 1 and the sleeve or barrel 5 the lengths of material will be caused to pass between the slots 3.

At a predetermined point intermediate the length thereof the sleeve or barrel 5 is intersected by the septum or partition 7, and suitably secured to one face of said septum or partition 7 is the socket member 8 having 95 its outer or open end terminating slightly

inwardly of the adjacent end of the sleeve or barrel 5. The socket member 8 is adapted to have detachably positioned therein a cake C of soap of a character generally employed 5 for shaving purposes.

In order to effectively maintain the cake C within the socket, we find it of advantage to provide the spring jaws 9. Each of the jaws 9 comprises a length of resilient wire 10 suitably anchored at one end to the inner wall of the socket 8 and having its opposite or free end portion angularly disposed, as indicated at 10, and directed through an elongated circumferentially disposed slot 11 15 produced in the wall of the socket at a point opposite to the connection between the jaw and the socket. A longitudinal margin of the slot 11 is provided with the teeth 12 with which the angular portion 10 of the jaw is 20 adapted to interlock so that said jaw may be held in requisite contact with the cake C.

In order to assure the proper coaction between the jaw 9 and the cake C, we find it of advantage to provide said jaw 9 at a point 25 substantially midway its length with the plate 14 which is adapted to contact directly with the cake C, and in view of the increased bearing surface afforded thereby, serves to effectively hold the cake C against 30 accidental displacement from within the socket 8. It is also preferred that the plate 14 be corrugated or crimped so that the same will impinge the cake C to further assure the maintenance of said cake within the 35 socket 8.

Suitably secured to the septum or partition 7 opposite to the socket 8 is a second socket 15 of such a length as to have its open or outer end arranged beyond the adjacent 40 end portion of the sleeve or barrel 5. The socket 15 is adapted to snugly receive the head H of a conventional shaving brush S.

It is to be noted that the cake C and the brush S are of such lengths as to be entirely 45 housed within the case 1 when the sleeve or barrel 5 is adjusted or moved to substantially the longitudinal center of the case 1, so that when the caps 2 are applied to said case, the cake C and the brush S are effectively protected against foreign substances 50 which would otherwise render both the cake C and the brush S unsanitary. It is also to be noted that when the barrel or sleeve 5 is adjusted to extend the cake C for use the brush S is still housed within the case 1 and vice versa, so that no obstruction or hindrance is given to the case 1 to prevent the same from being used as a manipulating 55 handle.

60 From the foregoing description, it is thought to be obvious that a toilet article constructed in accordance with our invention is of an extremely simple and compara-

tively inexpensive nature and is particularly well adapted for use by reason of the 65 convenience and facility with which it may be assembled, and it will also be obvious that our invention is susceptible of some change and modification without material departure from the principles and spirit 70 thereof and for this reason we do not wish to be understood as limiting ourselves to the precise arrangement and formation of the several parts herein shown in carrying out our invention in practice, except as herein- 75 after claimed.

We claim:

1. As a new article of manufacture, a toilet article comprising a case open at opposite ends, a member slidably positioned 80 within the case, and oppositely directed sockets carried by the slidable member.

2. As a new article of manufacture, a toilet article comprising a case open at opposite ends, a member slidably positioned 85 within the case, oppositely directed sockets carried by the slidable member, and a clamping means arranged within one of the sockets.

3. As a new article of manufacture, a toilet article comprising a case open at opposite ends, a member slidably positioned 90 within the case, and oppositely directed sockets carried by the slidable member, said sliding member being provided with means 95 extending exterior of the case whereby said member and case may be moved one relatively to the other in a direction longitudinally of the case.

4. As a new article of manufacture, a toilet article comprising a case open at opposite ends, a member slidably positioned 100 within the case, oppositely directed sockets carried by the slidable member, and a clamping jaw arranged within one of the sockets. 105

5. As a new article of manufacture, a toilet article comprising a case open at opposite ends, a member slidably positioned 110 within the case, oppositely directed sockets carried by the slidable member, a clamping jaw arranged within one of the sockets, and a plate carried by the jaw intermediate the length thereof.

6. As a new article of manufacture, a toilet article comprising a case open at opposite 115 ends, a member slidably positioned within the case, oppositely directed sockets carried by the slidable member, and a clamping jaw arranged within one of the sockets, said socket being provided with a slot 120 through which the free end portion of the clamping jaw extends.

7. As a new article of manufacture, a toilet article comprising a case open at opposite ends, a member slidably positioned 125 within the case, oppositely directed sockets

carried by the slidable member, and a clamping jaw arranged within one of the sockets, said socket being provided with a slot through which the free end portion of the clamping jaw extends, a marginal portion of the slot being toothed to afford a locking means for the jaw.

5 In testimony whereof we hereunto affix

our signatures in the presence of two witnesses.

WILBER H. THARP.
ALBERT T. ELLIAS.
